UNITED STATES PATENT OFFICE

HUMPHREYS MILLIKEN, OF MONTREAL, QUEBEC, CANADA

HIGH-POWER CIRCUIT-BREAKER

Application filed December 28, 1928. Serial No. 388,909.

This invention relates to that type of high-power circuit-breaker in which a blast of air or other fluid is employed for quenching the arc which occurs when the contacts are separated, and the special purpose of the present invention is to increase the arc-rupturing capacity of the device and thus prevent the arc coming into accidental contact with the main blade of the main contacts or some extraneous electric conductor, which of course would defeat the purpose of the air blast, as more fully hereinafter set forth.

Referring to the drawings annexed—

Fig. 1 is a vertical sectional view of a circuit-breaker embodying one form of my invention;

Fig. 2 is a horizontal sectional view on the line 2—2 of Fig. 1;

Fig. 3 is a horizontal sectional view taken on the line 3—3 of Fig. 1; Fig. 4 is a vertical sectional view taken on the line 4—4 of Fig. 1, the electro-magnetic device being omitted; Fig. 5 is a view similar to Fig. 1 showing a modified form of the device; Fig. 6 is a sectional view on the line 6—6 of Fig. 5; Fig. 7 is a plan view of another form of my circuit-breaker; Fig. 8 is a vertical sectional view of the device shown in Fig. 7; and Fig. 9 is a similar view of the modification shown in Fig. 7 taken at approximately a right angle to the line on which Fig. 8 is taken.

Referring to Figs. 1 to 4 of the drawings annexed by reference-numerals, 15 designates an air storage tank which is in communication, by means of a valved pipe 16, with the lower end of an insulator blast-tube 17. Mounted on the upper end of the insulator tube 17 is a nozzle 18 whose exit is directed upwardly and whose lower inlet end is in communication with the upper end of the blast-tube 17. This nozzle, as shown, is preferably in the form of a flattened or fan-shaped funnel and has its interior transversely divided by integral baffle-walls 19, these baffle-walls being arranged in two groups, one at either side of the vertical center of the nozzle, to thus form a free central passage 20 and two end passages numbered, respectively, 21 and 22. The baffle-walls, as shown particularly in Fig. 3, project alter-

nately from the opposite side walls of the nozzle, their lower ends terminating a suitable distance from the downwardly-and-inwardly-inclined edge walls of the nozzle.

The main contacts 23 are mounted on a metal sleeve-like support 24 which is supported on the insulator sleeve 17 by means of a plurality of well-known type of mushroom insulators 25. The main blade 26 of the switch is pivotally mounted on a vertical insulator structure 27 of suitable type. The terminals 28 and 29 of the circuits are connected, respectively, to the metal supporting-sleeve 24 and the pivotal end of the main blade 26. The shunt circuit is formed by attaching to the main blade 26 a horn 30 whose curved contact-rod extends horizontally through the nozzle, the holes in the edge walls through which this contact-rod portion of the horn extends being surrounded by two integral tubes 31 which project laterally from the nozzle a sufficient distance to prevent the arc-flame from escaping from the funnel at these points.

The other terminal of the shunt is indicated by 32; it extends through a hole in one of the tubes 31 so as to lie in the path of the contact-arm of the horn 30 and make contact therewith, the position of this shunt contact 32 being such as to draw the arc, when the shunt contacts separate by lateral movement of the horn 30 (with the blade 26) into the fan-shaped nozzle, where it will be acted on by the blast. It will be observed that this fixed shunt contact 32 is virtually in the interior of the nozzle, since the tube 31 is a lateral extension thereof. It will also be observed that this contact 32 is connected to the metal sleeve-support 24 through a terminal 33.

In the circuit between the fixed shunt 32 and the terminal 33 is an electromagnet 34 which is provided with three core-bars 35, 36 and 37 which have their pole-pieces extended laterally and upwardly so as to lie along-side of the outer faces of the walls of the nozzle, it being desirable to extend these pole-pieces entirely to the top-edge of the nozzle, as shown. The pole-pieces 36 are desirably located adjacent the passage 22 in the nozzle and the pole-pieces 35 adjacent the central passage 20, loc

while the remaining pole-pieces are located adjacent the passage 21.

Any suitable mechanism may be employed for admitting the compressed air into the nozzle at the moment of breaking the shunt contacts, and of course any suitable mechanism may be employed for operating the main switch-blade. I show such mechanisms in my Patent No. 1,756,374 dated April 29, 1930.

When the main blade is separated from its contacts, the circuit is, of course, shunted through the shunt contacts 30-32 and the electromagnet 34, thus energizing the pole-pieces 35, 36 and 37. The air blast from insulating pipe 17, having its shape changed by the fan-shape of the attenuator 18, blows through the passage 22, carrying the arc with it. At the same time, the magnetic pole-pieces 36 tend to force the arc outwardly through passage 22, thus greatly assisting the air blast in reducing the time of arc deflection and extinction. If the current is so large that the arc is not broken in the first passage 36, the horn, continuing its rapid motion, will draw the end of the arc farther to the left, and the air blast, aided by the magnetic pole-pieces 35 and 37, will force the arc upwardly into successive passages. As the arc is blown upwardly, it has no path to follow except the tortuous passages between the alternate baffles 10, and the length of the arc is thereby multiplied many times while its cross-section is confined to very small dimensions. The expansion of the arc atmosphere, due to heat, also assists in hastening the upward movement. The volume increase is entirely lengthwise of the arc.

The attenuator nozzle 18, together with its integral parts, is made of any insulating material which will not be damaged by an arc; material of this kind is now obtainable commercially, such as pyrex glass used for high-voltage insulators, this being much better than porcelain in that respect.

It will be observed that with my construction the arc is prevented from coming into accidental contact with the main blade or main contact and also that the arc is confined by the insulating walls to a small cross-section, but is stretched out to a great length while within the air blast, this increase of length of arc taking place much faster than the motion of the arcing horn. The arc is also cooled by coming into intimate contact with a great length of cool surface of the confining walls. It will be noted also that the deflecting motion of the arc is greatly accelerated by specially-arranged electromagnets.

Instead of air alone for the blast, the conductivity of the arc per unit volume may be reduced by injecting into the air blast gases or finely divided material, either solids or liquids, serving to cool the arc or otherwise reduce its conductivity. Also compressed

carbon dioxide, either in liquid or gaseous form, may be used for the purpose of providing a non-oxidizing atmosphere to extinguish flame due to burning of metal vapor; any other non-oxidizing material may be used, such as carbon tetrachloride.

It will be observed that the walls 19 are omitted at points 20, 21 between the pole-pieces of the magnets, this being for the purpose of reducing the air-gap of the magnetic circuits to a minimum and to thereby give a maximum magnetic force. The arc passages 20, 21 and 22 just at the point between the poles of the magnet may be made extremely narrow, such as $\frac{1}{16}$ inch thick. This extreme construction of the arc-spaced will increase its electrical resistance, thereby accelerating the reduction of the current to zero. The coil of the magnet 34 carries no current except while the circuit-breaker is in the act of opening, which is only a fraction of a second; this coil, therefore, may be made of smaller conductor than the main circuit, and low-voltage insulation between turns and between the iron core-pieces and the coil will be sufficient, as these parts are at the same potential substantially. The air-blast is opened slightly before the horn 30 is opened, as described in my aforesaid previous patent applications; this necessarily results in a slight waste of the air supply, but, in order to conserve the air supply, the contact-rod portion of the horn is made nearly as wide as the air-passage through the nozzle, so as to thereby delay the full flow of air until the instant it is required, i. e., when the arc arrives. The contact-rod portion of the horn may be made with a stream-line cross-section vertically, as shown particularly in Fig. 4, to avoid the formation of a partial vacuum on the upper side of the horn, which vacuum would reduce the dielectric strength of the atmosphere at that point. The attenuator-nozzle 18 may be sectional to facilitate its manufacture; I have shown, in Fig. 3, a nozzle made in two parts.

In the modifications shown in Figs. 5 and 6, the arcing-horn moves in a vertical plane. The main blade, not shown, may be arranged to move in either a vertical plane or a horizontal plane, and the arcing-horn may be arranged to open faster than the main blade. In this structure, the main discharge of the air is directed upwardly and laterally through a nozzle 18a divided by a partition-wall 18b. By varying the design, the portion of the air which flows out through the nozzle at opposite sides of the division-wall 18b may be varied, and it will be understood also that the two passages between this division-wall 18b and the end-walls of the nozzle may be provided with a baffle arrangement similar to that shown in Fig. 1.

In the modified form shown in Figs. 7, 8 and 9, the attenuator-nozzle 18c is virtually a straight tube provided with a plurality of

vertical baffles 19a. In this form of device, one of the tubes 31 is closed at its outer end to thus prevent escape of the air-blast at this point.

5 The switch is shown with a main contact and a shunt contact. It is quite possible, however, to omit the main contact and allow the "shunt contact" to become the main and only contact, in which case it would have
10 to carry the normal current continuously without overheating and would be made of suitable dimensions.

What I claim as new is:

1. In a circuit-breaker, a blast-pipe having an insulator nozzle connected to its exit-end, and a pair of separable contacts whose contacting faces are located in said nozzle so that the arc formed when the contacts are separated shall be subjected to said blast
20 entirely within the nozzle at a point distant from the exit-end of said nozzle, so that the arc will be confined by and attenuated within said nozzle, the side-walls of said insulator nozzle being depressed to bring them close
25 together at one point to form a narrow air-gap within the nozzle, and an electro-magnet included in the circuit and having its pole-pieces extending longitudinally of the nozzle and lying in the aforesaid depressions
30 in the nozzle.

2. In a circuit-breaker, a blast-pipe having an insulator nozzle connected to its exit-end, and a pair of separable contacts whose contacting faces are located within said nozzle
35 so that the arc formed when the contacts are separated shall be subjected to said blast entirely within the nozzle at a point distant from the exit-end of said nozzle, so that the arc will be confined by and attenuated within
40 said nozzle, the movable one of said contacts being in the form of a horn which extends through said nozzle and into the blast-pipe, so that the blast will be directed against the end of said horn and assist in quickly actuating
45 it in circuit-breaking direction.

In testimony whereof I hereunto affix my signature.

HUMPHREYS MILLIKEN.
